(57) **CLAIM**

We claim the ornamental design for portable focused beam
searchlight, as shown and described.

DESCRIPTION

FIG. 1 is a perspective view of a first embodiment of the
searchlight.

FIG. 2 is a front end elevational view of the first embodiment
of the searchlight looking through the face plate at the
reflector and xenon light source.

FIG. 3 is a top elevational view of the first embodiment of
the searchlight showing the top of the pushbutton control
switch.

FIG. 4 is a left side elevational view of the first embodiment
of the searchlight showing the left side of the pushbutton
control switch.

FIG. 5 is a right side elevational view of the first embodiment
of the searchlight showing the right side of the push-
button control switch.

FIG. 6 is a rear end view of the first embodiment of the
searchlight showing the recharging connector, which is
identical in the first and second embodiments.

FIG. 7 is a bottom elevational view of the first embodiment
of the searchlight opposite the top view of FIG. 3.

FIG. 8 is a perspective view of a second embodiment of the
searchlight with a filter attached to the front end.

FIG. 9 is a front end elevational view of the second
embodiment of the searchlight looking into the filter.

FIG. 10 is a top elevational view of the second embodiment
of the searchlight showing the top of the pushbutton control
switch.

FIG. 11 is a left side elevational view of the second
embodiment of searchlight showing the left side of the
pushbutton control switch.

FIG. 12 is a right side elevational view of the second
embodiment of searchlight showing the right side of the
pushbutton control switch; and,

FIG. 13 is a bottom elevational view of the second embodiment
of searchlight opposite the top view of FIG. 10.
